UNITED STATES PATENT OFFICE.

CHARLES L. RIPLEY, OF TOLEDO, OHIO, ASSIGNOR OF ONE-HALF TO LEO K. BARRY,
OF TOLEDO, OHIO.

MIXING APPARATUS.

Application filed April 13, 1928. Serial No. 269,622.

This invention relates to mixing apparatus, but more particularly to motor driven mixers of the type commonly used at soda fountains and elsewhere for mixing drinks, and an object of this invention is to provide a simple and efficient mixing apparatus in which the motor may be energized before the mixing element is clutched for operation, thereby to relieve the strain on the motor, and enhance the life of the parts. Another object is to enable a relatively large sized motor to be employed, and to so arrange the parts that a plurality of mixing elements may be selectively driven from a single motor. Other objects are to provide a new and improved mixing apparatus having the unique features of construction, arrangement and operation hereinafter described.

The invention is shown by way of illustration in the accompanying drawing, in which:

Fig. 1 is a side elevation partly in section of a mixing apparatus;

Fig. 2 is a transverse section on the line 2—2 of Fig. 1 showing one of the driving mechanisms and the switch-operating means of Fig. 1; and

Fig. 3 is a section on the line 3—3 of Fig. 1 showing the manner of supporting the bottom of the receptacle.

The illustrated embodiment of the invention comprises a mixing apparatus consisting of a standard having a base 1 and an upright support 2. Mounted on the upper end portion of the support 2 is an electric motor 3 having its axis horizontally disposed. Extending outwardly from the motor 3 and connected to be driven thereby, is a horizontal shaft 4, the outer end of which has bearing in a bracket 5, rising from horizontal supporting arm 6 suitably secured to the upright 2.

Mounted on the horizontal shaft 4 at spaced intervals are driving discs 7 having a concave surface 8. The discs 7 have a pin and slot connection 9 with the shaft 4 so as to permit limited sliding movements of the disc axially of the shaft, and the discs are yieldingly pressed in a direction away from the motor by coiled springs 10, one end of which abuts against the discs 7, and the opposite end bears against a collar 11.

Supported in sleeve bearings 12 depending from the horizontal arm 6, are vertically disposed mixing shafts 13 having their upper ends extending above the support 6, and on

which are mounted friction wheels 14. As shown, a vertical shaft is provided for each disc 7, and in the normal position of the parts the friction wheel 14 is positioned inwardly of the concave surface 8 of the respective driving disc and free from engagement therewith. In the normal position of the parts the motor driven shaft 4 is free to rotate without imparting movement to the vertical shafts 13.

Each shaft 13 is axially movable in its sleeve bearing 12, and when a shaft 13 is moved downwardly, its friction wheel 14 is moved into engagement with the peripheral portion of the associated driving disc 7, thereby to impart rotary movements to the vertical shaft 13. In order to effect such axial movement of the shafts 13, an actuating lever 15 is provided for each shaft 13. The lever 15 is pivotally mounted intermediate its ends on a bracket 16 rising from the horizontal support 6. One end of the lever 15 is provided with a fork 17 which straddles the shaft 13 in the space intermediate the collar 18 and the friction wheel 14.

Movement is imparted to the lever 15 by a vertically disposed rod 19 connected to the outer end of the lever 15 and guided by a bracket 20 secured to the support 6. Secured to the lower end of the rod 19 is a receptacle-engaging member 21 which is arcuately shaped, and is formed with a downwardly curled lip 22 engageable by the rim of a receptacle R containing the liquids or materials to be mixed, the receptacle being adapted to be slipped over the mixing shaft 13, as shown. The receptacle-engaging member is slidable vertically on a rod 23 having a stop 24, which limits the downward movement of the member. It is apparent that when the receptacle R is moved into engagement with the lip 22 and moved upwardly, the respective shaft 13 is thereby moved downwardly so that the friction wheel 14 is moved into frictional clutching engagement with the peripheral portion of the associated driving disc 7.

Prior to engagement of the friction wheel 14 with the driving disc, the electric motor 3 is energized so that the motor may reach approximately its maximum speed before a friction wheel is moved into engagement with its associated driving disc. For this purpose an arm 25 is mounted for movement with the lever 15, and is adapted to engage the spring arm 26 of a switch 27. In the movement of

the lever 15 the arm 25 moves the contact points of the switch 27 into engagement to energize the motor 3 prior to the movement of the friction wheel 14 into operative engagement with the associated driving disc 7 so that the motor is energized to rotate the discs 7 prior to the engagement of a friction wheel with its disc.

Upon releasing the receptacle R from the engaging member 21, a coiled spring 28 serves to swing the lever 15 in a counterclockwise direction (Fig. 2), thereby to successively disengage the friction wheel 14 from the disc 7 and then release the arm 25 to enable the spring arm 26 of the switch 27 to separate the contact points, thereby to de-energize the motor 3. The parts are maintained in this position until the receptacle R is again moved into position.

For supporting the bottom of the receptacle R, posts 29 rise from the base 1, and are provided with a button 30 shaped to receive the lower beaded edge 31 of the receptacle. In mounting the receptacle for mixing the upper rim of the receptacle is brought into engagement with the over-hanging lip 22, and the receptacle-engaging member 21 is forced upwardly until the lower beaded edge 31 of the receptacle can be mounted on the button 30 to hold the same in position. As shown, the posts 29 are substantially in alignment with the receptacle-engaging members 21.

While I have shown and described a construction which is the best form known to me at the present time, it is to be understood that numerous changes in details of construction, arrangement and operation may be effected without departing from the spirit of the invention, especially as defined in the appended claims.

What I claim as new and desire to secure by Letters Patent is:

1. A mixing apparatus comprising, in combination, an electric motor, a horizontal shaft connected to be driven by said motor, a driving disc mounted for rotation with said shaft, a vertical mixing shaft, a friction wheel on said vertical shaft engageable with said driving disc but normally free from engagement therewith, a lever pivoted intermediate its ends and having a fork on one end in engagement with said vertical shaft for moving said wheel into and out of engagement with said disc, a receptacle engaging member, a spring switch for said motor, a connection between said receptacle engaging member and said lever for imparting movements to the latter, and means movable with said lever for closing said switch before said wheel is moved into engagement with said disc by said lever.

2. A mixing apparatus comprising a standard, an electric motor mounted on the upper portion of said standard, a horizontal shaft connected to be driven by said motor, concave driving members on said shaft, vertically depending mixing shafts having friction wheels therein for engagement respectively with said driving discs, lever means for each shaft pivoted intermediate its ends and engageable with the respective vertical shaft for imparting axial movements thereto for moving said wheel into and out of driving engagement with the discs, an actuating member for each lever, a switch controlling said motor, and means associated respectively with said lever means for closing said switch prior to the operative engagement of the respective friction wheel with its associated driving disc.

In testimony whereof I have hereunto signed my name to this specification.

CHARLES L. RIPLEY.
